(57) CLAIM

I claim the ornamental design for a disposable footwear protector, as shown and described.

DESCRIPTION

FIG. 1 is a top perspective view of a disposable footwear protector showing my new design;

FIG. 2 is a right side view.

FIG. 3 is a left side view.

FIG. 4 is a front side view.

FIG. 5 is a back side view.

FIG. 6 is a top plan view; and,

FIG. 7 is a bottom plan view.

The broken lines in the drawings illustrate unclaimed environmental structure.
